UNITED STATES PATENT OFFICE.

CHARLES W. MERCER, OF GEORGETOWN, SOUTH CAROLINA.

THRUST-BEARING.

1,229,306.

Specification of Letters Patent. Patented June 12, 1917.

Application filed February 15, 1915. Serial No. 8,286.

To all whom it may concern:

Be it known that I, CHARLES W. MERCER, a citizen of the United States, residing at Georgetown, in the county of Georgetown 5 and State of South Carolina, have invented new and useful Improvements in Thrust-Bearing, of which the following is a specification.

This invention relates to improvements in 10 machines for grinding and chipping wood and bark used in the manufacture of paper pulp or fuel.

One object of the invention is to provide a 15 machine for this purpose in which a rotary cutter disk is so mounted that breakage of its cutting edges is avoided.

Another object of the invention is to provide 20 a coöperative working relation between the cutting parts of the machine.

Another object of the invention is to provide 25 a machine for grinding and cutting waste material which will successfully cut either large or small pieces of wood and thereby increase the capacity of the machine without danger of breakage of its parts.

Another object is to provide a machine of 30 the type indicated which will automatically widen the cutting space if any foreign material is introduced between the cutting edges.

A further object of the invention is to provide 35 a machine of the type indicated in which friction and power required for operation is reduced to a minimum.

The invention consists in the novel construction, arrangement and operation of 40 parts and will be more fully described and set forth in the following specification and claims, and illustrated in the accompanying drawings in which,

Figure 1 is a top plan view of the machine showing the hopper and the cutter disk with its resilient mounting;

Fig. 2 is a side elevation of the machine.

45 In the drawings like numerals indicate like parts.

The main rectangular frame 1 of the machine is formed preferably of metal and has the open central space 2. On either side of 50 the frame are bearing standards providing suitable bearings 3 and 4 for the shaft 5. This shaft extends beyond the frame on one side and is provided with suitable drive means or pulley 6. Mounted rigidly on the 55 shaft is a circular cutting disk or wheel 7. It will be observed that this is located over the opening 2 and adjacent the side of the frame farthest from the drive wheel and that the lower portion extends down below the plane of the frame. This disk 7 may be 60 of cast metal and is provided on one face with suitable openings (not shown) through which knife blades (not shown) carried by the disk project.

On the side of the frame adjacent the 65 front face of the cutter disk 7 is mounted a structure which will be known as the bed knife base 17. At the end of the bed knife base 17 adjacent the cutter disk each side of the bed knife base is recessed to form the 70 shelf 20. A bed knife 21 formed of two square pieces of tool steel is bolted to the base. It will be observed that these parts complete the continuity of the bed knife base.

The hopper 23 is fastened to the bed knife base by the bolts 24 or any other suitable means. The usual hopper opening 25 is noted but it will be observed that the bottom side of the inside of the hopper is formed with a 80 V similar in angle to the angle formed by the bed knives 21.

The automatic feature of the machine is made possible by the manner of mounting of the cutter wheel or disk and its shaft on the 85 bearing and the operative relation between these parts. A sliding movement of the shaft may take place toward the hopper until limited by suitable thrust bearings. A movement in the opposite direction is 90 limited by the operation of a spring held thrust bearing. Mounted loosely on the shaft 5 and free to rotate thereon is a thrust collar 26. This collar has its central opening enlarged at one end to receive an annular shoulder 27 formed on the shaft 5. Extending rearwardly from the thrust collar, on either side of the main shaft, are the rods 28 which pass through the bearings 3 or their standards and are free to move 95 therein. Bolts 29 extending rearwardly from the rear standards carry lugs or members 30 which provide at their upper ends suitable bearing openings for the rods 28 through the openings 31. Springs 32 on the 100 rods 28 abut against the members 30 and are tensioned by the nuts 33 which are threaded on the rods 28. Movement of the cutter disk and shaft away from the hopper will push the shoulder 27 against the thrust col- 110

lar 26 which in turn will move the rods 28 longitudinally. These in their movement will compress the springs 32 between the members 30 and the nuts 33, the ends of the rods sliding through the openings 31. Suitable oiling means and ducts 34 are located on the thrust collar to lubricate the bearing surface between the shoulder 27 and the collar 26.

10 A suitable metal casing or cover over the disk may be provided and this may be of any type but preferably should allow sufficient clearance for the rotation of the disk and for its sliding movement axially.

15 By using the apparatus described the capacity of machines of this type may be greatly increased. For instance in a mill where edgings and blocks are cut on the same machine, this machine will operate

20 with equal facility on either large or small pieces whether slabs or edgings. If a heavy slab is dropped into the hopper of this machine the weight of the slab against the cutting face of the disk will compress the 25 spring, allowing the disk to slide back and thereby giving the hog greater cutting capacity. As soon as the heavier pieces have been cut the springs will tend to return the disk to its normal position adjacent the 30 hopper opening where it will operate on the smaller pieces of material. Heretofore separate machines have been utilized to cut up different sizes of material, or devices have been used to stop the operation of the ma-

35 chine if the material being cut was too heavy or coarse. Some of these devices provided parts which were designed to break in order to relieve the strain on the cutting knives.

40 All of these machines have been greatly limited in the scope of their work by the rigidity of the parts, but this machine provides means for relieving the strain from the cutter knives by the combined effect produced by the coöperation of the spring held 45 slidably mounted rotary cutter disk and the base knife.

These features provide a wood hog machine having a wide range of usefulness. Friction is reduced, less power is required 50 to operate the machine and time and expense for repairs is reduced to a minimum. It will be obvious that the same result could be had by keying the cutter disk to slide on the shaft, but so arranged as to turn with it.

55 Changes in form, material, and location of the individual parts of the machine may be made without departing from the scope of the invention.

What I claim is:

60 1. In a machine of the character described, the combination of a rotary shaft, a revolute member mounted on the shaft, a thrust collar loosely mounted on said shaft adjacent said revolute member, and spring held means coöperating with said thrust col-

lar to normally hold said thrust collar in one extreme position and permit axial movement of the revolute member.

2. In a machine of the character described, a rotary shaft, bearing standards 70 and bearings for said shaft, a revolute member mounted on said shaft, a thrust collar loosely mounted on said shaft adjacent said revolute member, rods on either side of said shaft engaging with and extending 75 from said thrust collar, supporting bearings for said rods, springs on said rods abutting against said supporting bearings, and adjusting means secured to said rods for tensioning said springs, axial movement of said 80 revolute member causing a similar axial movement of said thrust collar and subsequent movement of said springs, which latter permit axial movement of the revolute member and tend to normally hold said revolute member in one extreme position. 85

3. In a machine of the character described, a rotary shaft, bearing standards and main bearings for said shaft, a thrust collar loosely mounted on said shaft, an 90 annular boss adjacent to said thrust collar and rotated by said shaft, rods substantially parallel to and on either side of said shaft engaging with and extending from said thrust collar, supporting bearings for said 95 rods, springs mounted in conjunction with said rods, and adjusting means for tensioning said springs, axial movement of said annular boss causing a similar axial movement of said thrust collar and subsequent 100 movement of said springs whereby axial movement of said rods, thrust collar and boss is permitted.

4. In a machine of the character described, a rotary shaft, bearing standards 105 and main bearings for said shaft, a thrust collar loosely mounted on said shaft, an annular boss adjacent to said thrust collar and rotated by said shaft, rods substantially parallel to and on either side of said shaft 110 engaging with and extending from said thrust collar, to a point beyond one of the main bearings, supporting bearings for said rods on the opposite side of said main bearing from said thrust collar, springs mounted 115 in conjunction with said rods, and adjusting means for tensioning said springs, axial movement of said annular boss causing a similar axial movement of said thrust collar and subsequent movement of said springs 120 whereby axial movement of said rods, thrust collar and boss is permitted.

5. In a machine of the character described, a main frame, main bearings mounted on either side of said main frame, 12 a rotary shaft supported on said bearings, a revolute member mounted on said shaft and between said bearings, a thrust collar loosely mounted on said shaft adjacent said revolute member, an annular boss between said 125

revoluble member and said thrust collar and rotated by said shaft, rods substantially parallel to and on either side of said shaft engaging with and extending from said thrust collar to a point beyond one of said main bearings, supporting bearings for said rods mounted on and carried by said main frame and on the opposite side of said main bearing from said thrust collar and revoluble member, springs mounted in conjunction with said rods, and adjusting means for tensioning said springs on the opposite side of

said main bearing from said revoluble member, axial movement of said revoluble member causing a similar movement of said boss, 15 thrust collar and rods and the tensioning of said springs.

In testimony whereof I have hereunto set my hand in presence of two subscribing witnesses.

CHARLES W. MERCER.
